UNITED STATES PATENT OFFICE.

JEAN B. VIROLET, OF PARIS, FRANCE.

DESIGN FOR OIL-CLOTH.

Specification forming part of Design No. 7,627, dated August 11, 1874; application filed July 11, 1874.
[Term of Patent 3½ years.]

CASE B.

To all whom it may concern:

Be it known that I, JEAN B. VIROLET, of Paris, France, have invented a Design for Oil-Cloth, of which the following is a specification:

The nature of my design is fully represented in the accompanying photograph, to which reference is made.

The design is mainly intended for rugs, but it is also applicable to other forms.

The design consists of the landscape A in the center of the rug, with figures of a brood-partridge and her young in the middle ground, the whole being surrounded by the border B. The design also consists of the rams' heads and ornamental figures E at the sides and angles of the aforesaid center, and the border F surrounding the space containing the heads and figures. The design also consists of the figures of the lakes G with swans H afloat thereon, and shore-views D in the distance, also the ornamental figures I, J, and K, and the border L, in the middle ground of the rug surrounding the center-piece, and the border F. The design also consists of the plain space with the ornamental figures N, O, and P separating the middle ground from the margins Q. The design also consists of the shields R and sheep-heads S at the angles of the margins Q, also the figures of young partridges T, and the foliate figures U in said margins. The design also consists of the inner border

V, and the outer margin W surrounding the whole.

Having thus described my invention, I claim as new and desire to secure by Letters Patent—

1. The design for oil-cloth, consisting of the center landscape A, figures of the partridge and young, and the border B surrounding the same, as shown and set forth.
2. The design for oil-cloth, consisting of the rams' heads C, ornamental figures E, and border F, as shown and set forth.
3. The design for oil-cloth, consisting of the lakes H, swans G, shore-views D, ornamental figures I J K, and border L, as shown and set forth.
4. The design for oil-cloth, consisting of the plain space M, with ornamental figures N, O, and P surrounding the middle ground, as shown and set forth.
5. The design for oil-cloth, consisting of the shields R, sheep-heads S, chick-partridges T, and foliate figures U in the margins Q, as shown and set forth.
6. The design for oil-cloth, consisting of the borders V and W of the margins of the rug, as shown and set forth.

J. B. VIROLET.
